CLAIM

The ornamental design for a multimeter holster, as shown and described.

DESCRIPTION

FIG. 1 is a top plan view of a multimeter holster showing our new design;

FIG. 2 is a right side elevational view;

FIG. 3 is a front elevational view;

FIG. 4 is a rear elevational view;

FIG. 5 is a bottom plan view;

FIG. 6 is a left side elevational view showing the rear support extended, the dotted line showing of an instrument is for illustrative purposes only and forms no part of the claimed design; and

FIG. 7 is a top, front, and right side perspective view thereof.
